UNITED STATES PATENT OFFICE.

JAMES DUNN AND FRANK H. JENNINGS, OF PHILADELPHIA, PENNSYLVANIA, ASSIGNORS OF ONE-THIRD TO CHARLES BAUMANN, SR., OF PHILADELPHIA, PENNSYLVANIA.

HINGE.

No. 834,111.

Specification of Letters Patent.

Patented Oct. 23, 1906.

Application filed April 13, 1906. Serial No. 311,587.

To all whom it may concern:

Be it known that we, JAMES DUNN and FRANK H. JENNINGS, citizens of the United States, residing at Philadelphia, in the county 5 of Philadelphia and State of Pennsylvania, have invented a new and useful Hinge, of which the following is a specification.

This invention relates to hinges, more particularly to the hinges operating to automatically close doors, shutters, and similar devices to which they are attached, and has for its object to produce a simply-constructed device of this character of increased efficiency, durability, and utility.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation.

The improved device is more particularly applicable to the larger class of doors and shutters of a fireproof character and for the purpose of illustration is shown applied to a conventional form of a structure of this character.

In the drawings thus employed, Figure 1 is a front elevation of a portion of a shutter and the adjacent walls of a building with one of the improved hinges applied. Fig. 2 is a plan view of the shutter and one of the improved hinges with the wall of the building above the shutter in section. Figs. 3 and 4 are perspective views of the two leaf portions of the improved hinge detached. Fig. 5 is a view of the fusible locking-rod detached.

The shutter is indicated at 10, of any approved material, but preferably of fireproof material, arranged over the usual opening in the wall 11.

The improved hinge consists of two leaves having a pintle upon one leaf and a pintle-socket upon the other leaf, the socket-leaf 50 represented at 12 and the pintle-supporting leaf represented at 13, the leaf 13 being attached to the shutter, as by screws 14, and the leaf 12 attached to the walls 11, as by screws

15. The pintle is connected at 17 to the leaf 13 and operating through the socket 18 on the leaf 12. The leaves 12 13 are preferably formed from plates of metal, with the pintle-supporting portion 17 and the socket 18 integral with the leaves, or bent therefrom, as shown. The leaf 12 is provided with outwarded portions 19 20 at right angles to each other and perforated to receive the ends of a compound curved rod 21, the rod forming a track for a bearing-wheel 22, supported in ears 23 24 on the leaf 13. The track 21 is in 60 semicircular form on a horizontal plane, as shown in Fig. 2, and inclined upwardly from the member 20 to the member 19, so that as the shutter 10 is opened the roller 22 in riding upon the track will carry the shutter upward 65 with it, and when released the gravity of the shutter will cause the same to automatically close, as will be obvious. The track is formed from a round rod, preferably of steel, and thus presents a round surface constantly to 70 the roller 22, so that no material will gather upon the track to obstruct it. Thus in the winter-time if snow or ice should gather upon the track the first time the shutter is opened or closed the roller would quickly 75 break the ice or snow loose from the track, which would fall therefrom, so that the presence of the ice or snow would not prevent the action of the device or clog the same.

The parts are simple in construction, can 80 be inexpensively manufactured, and applied to the various sizes of shutters and doors in use. Attached to the inner face of the shutter is an eye 25, and attached to the wall 11, preferably within the opening covered by the 85 shutter, is an eye 26, and looped into the eye 25 is a rod 27, and detachably hooked at 28 into the eye 26 is another rod 29, the free ends of the rods being coupled into a fusible plug or collar 30. The rods 27 29 are thus coupled 90 rigidly and form a stay to hold the shutter in open position, and in event of a fire the heat radiating therefrom will fuse the plug 30, and thus release the shutter, which will immediately close automatically by running down 95 the inclined track 21, as before described.

Having thus described the invention, what is claimed as new is—

1. In an apparatus of the class described, a structure having an opening, a closure to said opening, a hinge member having spaced lat-

eral offsets and a pintle-socket, an inclined track connected at the ends respectively in said offsets, a hinge member connected to said closure and provided with a pintle engaging said pintle-socket and a bearing engaging said track.

2. The combination with a structure having an opening, a closure for said opening, a hinge element having a pintle-socket and spaced lateral offsets, tracks formed from circular rods and connected at the ends in said said offsets and inclined upwardly, and a

hinge member connected to said closure and provided with a pintle engaging said socket and with bearings engaging said tracks.

In testimony that we claim the foregoing as our own we have hereto affixed our signatures in the presence of two witnesses.

JAMES DUNN.
FRANK H. JENNINGS.
